UNITED STATES PATENT OFFICE.

HERMAN W. WINANS, OF NEW YORK, N. Y., ASSIGNOR TO JOHN K. FORD,
OF SAME PLACE.

BRAIDING-MACHINE.

SPECIFICATION forming part of Letters Patent No. 313,905, dated March 17, 1885.

Application filed January 23, 1883. (No model.)

To all whom it may concern:

Be it known that I, HERMAN W. WINANS, of New York city, in the county and State of New York, have invented certain new and useful Improvements in Braiding Machines; and I do hereby declare that the following is a full and exact description thereof.

The object of the invention is to produce a machine for making square braids from cotton-yarns applied in successive layers one exterior to the other, either with or without a rubber core, the completed article to be used as packing for the stuffing-boxes of steam-engines or for other purposes.

15 The invention is illustrated in the accompanying drawings, which form a part of this specification, and in which—

Figure 1 is a plan view, and Fig. 2 a side elevation, of a machine embodying my invention. Fig. 3 is an elevation of a portion of the machine, taken at right angles to the view in Fig. 2. Fig. 4 is a vertical detail section showing one of the yarn-guides and a yarn being led up out of it. Fig. 5 is a plan view 25 of the shaping-die, and Fig. 6 is an elevation of one of the parts composing the die.

Referring to the drawings, A designates the rigid frame of the machine, and B B' are sets of bobbin-carriers supporting bobbins which 30 deliver cotton-yarns upward through guides P. The yarns on emerging from these guides converge, and as the carriers B B' are traversed by ordinary mechanism, delivering the yarns under a uniform or nearly uniform tension, a 35 closely-woven cover is braided around the core l, led up from below through the center of the machine. The completed braid is carried partially around two slowly-rotating feed-wheels, and thus caused to move slowly upward, while 40 the bobbin-carriers B B', traversing in opposite directions below, properly interlace the several yarns and produce a braided tube, m, around the core l.

The bobbin-carriers are traversed in their 45 races by the usual forked or slotted carriers, which are operated by a train of connected gearing, these parts being substantially in construction and operation the same as shown in the Patent No. 191,641, of June 5, 1877.

The braid, so far as yet described, would be 50 produced in a cylindrical form, or nearly so; but I resist this tendency by introducing in each successive layer of braid four longitudinal yarns, n, which are arranged equidistant from each other and serve to build up four 55 corners. These yarns n are led up from bobbins, (not shown,) and are conducted through guides P, and led into the correct position under the covering or tube m. A stationary guide, T, which I term a "core-die," receives 60 and guides the core l. The hole in the center of this core-die T should be of the size and form of the core l. The yarns n are brought into the proper relation to the core l by being introduced into notches w, formed in the corners of a larger die, W, above. The die W has a rectangular passage through it, slightly flaring at the bottom, and of a size to match closely to and to smooth and finish the resulting product after the cover m has been braided on 70 the core l.

I can make a successful braid by braiding as described a covering, m, in a uniform layer around a compound core composed of the core l and four yarns, n, extending equidistant 75 along its surface. In such case the covering m would be entirely exterior to the longitudinal yarns.

I prefer another construction, which I will now describe. The guides P stand in the spaces 80 A' in the frame A, between the paths or races of the several bobbins, and their heights are about equal to those of the several bobbin-carriers, B B'. As the bobbin-carriers traverse successively in their several races alternately 85 outside and inside of each guide P they braid the covering m with the corner yarns n embraced within its structure. By placing the guides P at equidistant points, as shown, and guiding the yarns n therefrom accurately into 90 position by the notches w in the die W, the yarns n are placed properly to build up the four corners of the braid. Whether the yarns n are braided in the structure m or are laid at four corners independently, they serve to 95 build up those corners, and the braided article passing up through the flaring aperture in the die W becomes pressed and shaped into

a smooth rectangular body. The wheels X Y feed the braid slowly forward and upward. The first wheel, X, is finely toothed, to aid in its taking a firm hold on the covering m . The other wheel, Y, may be smooth. The braid is led from this take-up mechanism to a bobbin, on which it is smoothly wound. In case several layers of braid, m , and corner yarns are to be applied, the operation is repeated on 10 the same machine, or on a corresponding machine with larger dies T and W, the article produced by one operation serving as a core for the subsequent similar operation. The sizes and firmness of the yarns n in their relation 15 to the yarns of the cover m should be adapted to each other with the desired purpose in view.

The dies T and W are made in two parts, held together in a suitable frame, Y', by screws V, as seen in Fig. 5. This construction will 20 allow the ready change of dies of one size for those of another size of interior passage.

The traversing ways for the bobbin-carriers may be formed approximately in the figure of

a square instead of in a circle, as shown, and a different number of carriers may be used. 25

What I claim as new is—

1. The combination, with the die W, made in two parts, as shown, of the frame Y' and screws V, the corner guides, P, the carriers B B', and the mechanism for traversing said carriers in opposite directions, as set forth. 30

2. The upper die, W, having notches w , adapted to guide the yarns n , as described, combined with the core-die T, bobbin-carriers B B', means for traversing them in opposite directions, and the take-up mechanism, as herein specified. 35

In testimony whereof I have hereunto set my hand, at New York city, this 31st day of October, 1882, in the presence of two subscribing 40 witnesses.

HERMAN W. WINANS.
